CLAIM

I claim the ornamental design for a shoe sole, as shown and described.

DESCRIPTION

FIG. 1 is an isometric view of a shoe sole showing my new design, the broken line showing the shoe upper in FIGS. 1, 4, 5, 6 & 7 representing the portion of the design that forms no part of the claim;

FIG. 2 is a bottom plan view;

FIG. 3 is a top plan view;

FIG. 4 is a left side view;

FIG. 5 is a right side view;

FIG. 6 is a front view; and,

FIG. 7 is a rear view.
